UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed December 29, 1927. Serial No. 243,288.

This invention relates to improvements in car construction.

One object of the invention is to provide a railway car underframe construction of exceptionally great strength, combined with draft rigging means, including column means extending from end to end of the car actuated in both buff and draft, wherein the column means is movable with respect to the underframe construction, thus functioning as a continuous drawbar combined with shock absorbing means at opposite ends of the car operated simultaneously to provide a relatively long movement of the column with respect to the car proper, to absorb the shocks without substantial elongation of the train of cars in draft, or shortening of same in buff.

Another object of the invention is to provide in a railway car, mechanism of the character indicated, including a column adapted to transmit the draft and buffing shocks simultaneously to shock absorbing means at opposite ends of the car, wherein the forces are transmitted from the shock absorbing means to the bolsters of the car underframe.

A more specific object of the invention is to provide in a car underframe structure, fixed center sill members, a movable column member co-operating therewith, the column member being continuous from end to end of the car and adapted to receive buffing and draft forces through drawbar elements suitably connected to the opposite ends of the column, together with shock absorbing means co-operating with the bolsters at opposite ends of the car and means for simultaneously actuating said shock absorbing means upon relative movement of the column member and center sills, whereby relatively great movement of the parts is obtained substantially equal to the combined permissible compression stroke of all of said shock absorbing means.

A further object of the invention is to provide a compression member independent of the car body structure for transmitting the forces to the shock absorbing mechanisms which co-operate with the body bolsters, thereby preventing buckling or distortion of the car body and underframe structure.

Another object of the invention is to provide in a mechanism of the character indicated, a drawbar element or coupler, together with yoke means, and means for connecting the drawbar to the yoke, wherein means is provided for supporting the coupler end of the drawbar shank for bracing the same to prevent tilting or drooping thereof.

Other and further objects of the invention will more clearly appear from the description and claims hereinafter following:

In the drawings forming a part of this specification, Figure 1 is a longitudinal, horizontal, sectional view of the forward end portion of a car underframe structure, partly broken away, illustrating my improvements in connection therewith. Figure 2 is a longitudinal, vertical, sectional view, corresponding substantially to the line 2-2 of Figure 1. Figure 3 is a vertical, transverse, sectional view, corresponding substantially to the line 3-3 of Figure 2. Figure 4 is a vertical, transverse, sectional view, corresponding substantially to the line 4-4 of Figure 2. Figure 5 is a horizontal, longitudinal, sectional view, on a reduced scale, showing the underframe structure from end to end of the car, partly broken away, illustrating my improvements in connection therewith in detail, as shown in Figures 1, 2, 3 and 4. And Figure 6 is a horizontal sectional view of one end of a car underframe structure illustrating a different embodiment of my invention.

In said drawings, 10-10 indicate the front and rear body bolsters of a railway car underframe. End sill members 11 of the usual form are provided at the front and rear ends of the car underframe, the end sill members being united to side sill members 12, which are also secured to the body bolster 10. A plurality of cross-tie members 13 are employed as commonly used in railway cars, to brace the side sills and also serve as floor supports. Reinforcing truss beams 14 are preferably provided, as shown in Figure 1, to brace the end sill and bolster construction, the truss members 14 extending diagonally from each bolster at a point adjacent its connection with the central structure of

the car underframe outwardly to the corners of the same and being suitably secured to the bolsters proper and the end and side sills. 15—15 designate the usual drawbars which are employed at opposite ends of the underframe construction.

My improved car construction comprises broadly longitudinally disposed sill-like members A—A, which are fixed to the underframe structure; a column element B; friction shock absorbing means C—C at each end of the car; two yoke members D—D; two key members F—F for securing the yokes to the drawbars; shock absorbing means G in the form of a spring co-operating with each yoke and drawbar; longitudinally disposed pressure transmitting members H—H, extending from end to end of the car and serving as movable draft sills; two follower members K—K co-operating respectively with the front and rear drawbars 15 and yoke D; and the novel bolster and underframe construction as hereinafter pointed out.

The bolsters 10 at the opposite ends of the car are of the same design, each being made up of a plurality of members. Each bolster 10 comprises a top plate member 16, extending across the car; bottom plate members 17—17 extending inwardly from the side sills 12 and having their inner ends spaced apart, as most clearly shown in Figure 3; front and rear diaphragm plate members 18—18, connected to the top and bottom plates 16 and 17, and the side sill members 12, and having their inner ends spaced apart, as shown in Figure 3. The top and bottom plate members 16 and 17 are braced by transverse reinforcing members 19—19, having top and bottom horizontally disposed flanges suitably secured to the inner sides of the plates 16 and 17. Each bolster 10 is provided with a central casting 20, which is of the construction as most clearly illustrated in Figures 1, 2 and 3. The casting 20 comprises a main base portion, having laterally extending supporting brackets or shelf-like members 21 secured to the bottom sides of the plates 17 adjacent the inner ends thereof.

The central portion of the base member of the casting or filler 20 is extended upwardly, as most clearly shown in Figure 3, thereby providing longitudinally disposed side abutment surfaces 22—22 on opposite sides thereof. Transversely disposed angle members 23—23 are arranged at the inner ends of the plates 17, each of the angle members 23 having the horizontal portion thereof forming a continuation of the adjacent plate 17. The vertically disposed portion of each angle member 23 abuts the vertical face 22 of the upward extension on the casting 20. The central portion of the casting 20 is also provided with upstanding spaced walls 24—24, joined by a transverse end wall 25. The walls 24—24 and 25, together define an abut-

ment member for the shock absorbing mechanism C, as hereinafter more clearly pointed out. As shown in Figures 1 and 2, the walls 24 of each bolster filler casting 20 are cut away at the outer ends thereof, as clearly illustrated in Figure 2. Each of the castings 20 is also provided with the usual vertically disposed center pin receiving openings 26. At the upper edges, the walls 24 are joined by a relatively narrow web 27, as clearly illustrated in Figure 2, which serves as a tie for the walls 24 and a support for the top plate 16 of the bolster. The end wall 25 of the abutment member projects upwardly beyond the top of the web 27, thereby affording an abutment against the inner edge of the top plate 16 of the bolster. Longitudinal sills A—A are in the form of angle beam members which extend longitudinally of the car from substantially one end to the other thereof, and are secured at suitable intervals to the cross-ties 13, the top plates 16 of the bolsters and the end sills 11. The vertical portions of the angle beams A are joined to the vertical portions of the angle members 23 by means of heavy reinforcing plates 28, which have their opposite ends extending beyond the sides of the bolsters 10. As will be evident, the angle beams A form, in effect, longitudinally disposed spaced center sills of the railway car underframe. As most clearly illustrated in Figures 1 and 3, the walls 24—24 of each of the castings 20 of the bolsters 10 are spaced such a distance from the plates 28 that the pressure transmitting members H will be accommodated therebetween for free longitudinal movement. Upon reference to Figures 1 and 2 of the drawings, it will be evident that the body bolster is of much greater width than is the usual practice, the same projecting for some distance beyond the front and rear sides of the truck bolster. This is for the purpose of strengthening same to compensate for the cutting away of the body bolster to accommodate the passage therethrough of the members H. It will also be noted, upon reference to Figure 2, that the bottom portion of the body bolster is reinforced by longitudinally extending spaced ribs at the front and rear thereof, the outer ribs being considerably deeper than the inner ribs. Inasmuch as the body bolster is of greater width than the truck bolster as hereinbefore pointed out, there is sufficient room between the front and rear faces of the truck bolster and the outer ribs of the body bolster to permit the necessary pivotal or swinging movement of the body and truck bolsters with respect to each other, when the car is rounding a curved track. These ribs, together with the abutments 22 greatly reinforce the bolster against vertical load especially, and add greatly to the strength of the bolster. It is also pointed out that wear plates are interposed between the bottom member of the casting 20 and the

longitudinal movable members H, thereby preventing wear of the casting. It will be obvious that the wear plates may be readily replaced when they become damaged or worn.

5 The members H are in the form of channel bars or beams extending for substantially the entire length of the car. The channel beams H are spaced apart, as shown, and are joined at opposite ends by tie plates 30—30 and 10 31—31. The tie plates 30 at each end of the car are disposed on top of the channel members and serve as cover plates therefor, being suitably secured to the top and bottom flanges of the channel members. The plates 31 at 15 each end of the car are secured to the lower flanges of the channel beams H and, as shown most clearly in Figure 2, extend to the outer extremities of the members H. For a purpose hereinafter described, each plate 31 is made 20 in several sections, the two outermost sections at each end being removably attached to the beams H. The outermost section is flanged upwardly at either side past the lower flange of the adjacent beam H, these 25 flanges serving the double purpose of a retainer for the draft key F and a wear plate between the member H and the adjacent side walls of the buffer casting. The channel members H are directly supported by the 30 body bolster, and the outer ends thereof are guided by the carry-irons 32 which are supported from the underframe structure in any well known manner. Each of the carry irons 32 is provided with a wear plate 33, which 35 serves as a direct supporting means for the bottom tie plate 31 at the same end of the car. Between the bolsters 10, the channel members H are also united by top and bottom tie plates 40 34 and 35, two such tie plates being employed adjacent each bolster and additional similar top and bottom plates may be provided at spaced intervals therebetween, the bottom plates being removably attached for a purpose hereinafter described. As most clearly 45 shown in Figure 2, the tie plate 34 is secured to the top flanges of the channel members H, while the tie plate 35 is secured to the bottom flanges thereof. The tie plates 30 and 31, and 34 and 35 of each set have their outer 50 ends normally spaced from the corresponding bolster 10, so as to permit the required amount of relative longitudinal movement between the members H and the car underframe. Adjacent the front and rear ends thereof, the channel members H are provided with stop castings 36—36. The stop castings, as most 55 clearly shown in Figure 1, are of a length equal to the width of the bolster center casting 20, and in the normal position of the parts have their front and rear ends in substantial alignment with the front and rear sides of the corresponding bolster center casting. As clearly illustrated in Figure 3, each 60 of the walls 24 of the casting 20 and the adjacent plate 28 of each bolster 10 are spaced a

sufficient distance apart to accommodate one of the stop castings 36, and the channel member H to which it is attached for free movement longitudinally therebetween. The stop castings 36 are secured to the vertical webs of the channel members H in any suitable manner, the same being herein shown as secured by rivets. The channel members H are also provided with additional stop castings 37 at the extremities thereof, one set of said stop castings being clearly illustrated in detail in Figure 1. As shown, the stop castings 37 are arranged in pairs and secured to the channel members H by rivets. Each set of stop castings 37 is provided with a transverse key receiving opening 38 registering with similar key receiving openings 39 in the two channel members. Rearwardly of the key receiving openings 38, the stop castings 37 are provided with aligned recesses 40, adapted to accommodate a follower plate K.

The drawbar 15 at each end of the car is secured to the yoke member D at the same end of the car by a transverse key F extending through a transverse opening in the yoke and having the opposite ends thereof accommodated within the openings or slots 38 and 39 of the stop castings 37 and the channel members H. As shown, the yoke member D is provided with forwardly extending side walls 42—42 through which the key passes, and a bottom wall 43 and top wall 41 connecting the side walls 42. The bottom wall 43 is substantially continuous with the main yoke portion of the member D and projects forwardly beyond the side walls 42, thereby providing an extension or shelf which directly supports the shank of the drawbar 15. Each yoke D is directly supported upon the sectional lower tie plate 31 at the corresponding ends of the channel members H, and the tie plate 31 in turn is supported by the wear plate 33 on the carry iron 32. The follower K and the spring element G are disposed within the yoke D. The follower K is held against relative movement with respect to the channel members H by the front and rear end walls of the openings or recesses 40 in the stop castings 37. As most clearly shown in Figure 1, there is a slight clearance between the inner edge of the key F and the end walls of the openings in the yoke side walls 42, and there is also a slight clearance between the follower K and the front wall of the opening in the yoke member proper. The slots or openings 38 and 39 of the stop castings 37 and the channel members H are of greater length than the width of the key F, so that a certain amount of relative movement is permitted between the key and these members when a draft action is applied to the drawbar 15.

The friction shock absorbing mechanisms C, which are disposed at opposite ends of the underframe structure of the car, are of the

usual design and therefore the structure thereof is not illustrated in detail. The type of shock absorbing mechanism employed comprises the usual friction shell and friction shoes co-operating therewith, actuated by a wedge member, the wedge member being shown as projecting outwardly of the shell and is designated by 44. As shown, the casting or shell of the shock absorbing mechanism at each end of the underframe structure has the end wall thereof normally bearing on the abutment 25 of the bolster 10 at the same end of the car and is adapted to co-operate with the stop castings 36 at that end of the car in the manner of the usual follower.

The column element B is directly interposed between the wedge members 44 of the friction shock absorbing mechanisms at the opposite ends of the car. This column member B is adapted to directly transmit the actuating force from one shock absorbing mechanism to the other. As most clearly illustrated in Figures 1 and 4, the column member B comprises two longitudinally disposed channel members 45—45, having the web portions thereof vertically disposed and securely tied together and braced by additional channel members 47—47, the web portions of the latter members being horizontally disposed and arranged back to back, and the flanges thereof being securely attached by rivets or other suitable means to the web portions of the channels 45—45. As shown, a combined tie and wear plate 46 is secured to the bottom flanges of the channel members 45. The channel members 45 are further provided at each end with longitudinally extending bracing members 48 at the opposite sides thereof, the bracing members 48 having outwardly directed flanges 49 at the outer ends thereof and being further provided with vertically arranged corrugations 50 at spaced intervals, these corrugations serving to guide the member B and keep it properly centered between the channels of the member H. The front and rear ends of the column B are closed by abutment plates 51—51, which are secured to the flanges 49 of the reinforcing members 48, and are also secured to angle plates 52 secured to the outer ends of the horizontally disposed channel members 47—47. It will be evident that a pressure transmitting column element is thus provided, of exceptionally great strength.

At each end the underframe of the car is provided with the usual striking casting 53, which is secured to the end sill construction in a well known manner. A horizontally disposed gusset plate 54 is also provided at each end of the car for reinforcing the end structure of the underframe, the plate 54 being secured to the end sill 11 and the center sill members A. Additional vertically disposed flanged gusset plates 55—55 are secured to the ends of the members A and the adjacent

end sill 11 and striking casting 53, the lower flange of each plate 55, together with the casting 53 providing means for the attachment of the supporting plate 32.

From the preceding description, taken in connection with the drawings, it will be evident that I have provided a bolster construction which may be partly disassembled in order to facilitate the assembling of the movable members H, together with the shock absorbing mechanism C and column element B with the underframe structure, and the removal of these parts therefrom. In order to disassemble the parts, it is merely necessary to jack up the body of the car relative to the trucks, detach the castings 20 from the bolsters 10 and the carrier plate 32 from the end sill structure and then remove the channel members H, together with the parts attached thereto, either by dropping the same vertically from between the center sills A, or endwise from the car. Couplers 15 and yokes D, with associated parts may be removed without disturbing the member H or bolster casting 20 by removing the plates 32 and thereafter detaching the plates 31 directly under the yokes D. The draft gear members C and the column member B may also be removed without disturbing the remaining car structure in a similar manner, simply by detaching the supporting plates 35 and other similar plates attached to the lower flanges of the members H.

The operation of the shock absorbing mechanism of my improved underframe construction, assuming a buffing action being applied to the drawbar 15 at the left-hand end of Figure 1, is as follows: The drawbar 15 will be forced inwardly and carry the channel members H therewith, due to the direct abutment of the drawbar on the fixed follower K. As the channel members H are carried to the right in Figure 1, the stop castings 36 will force the friction shell of the shock absorbing mechanism C adjacent the bolster 10, to be carried inwardly also. Due to the action of the column element B, the shock absorbing mechanism C at the opposite end of the car will be compressed between same and its adjacent bolster in unison with the shock absorbing mechanism first referred to. Movement of the second mentioned shock absorbing mechanism C, which is actuated through the column element B, relative to the car body, will be prevented by engagement with the abutment member 25 of the bolster 10 at the corresponding end of the car. The compression of the two shock absorbing mechanisms at the opposite ends of the car will thus continue until compression thereof is limited by the opposite ends of the column coming into engagement with the casings or shells of the friction shock absorbing mechanisms. It will be evident that by providing the two simultaneously

operated friction shock absorbing mechanisms, the movement of the channel members H will be twice as much as it would be if a single shock absorbing mechanism were employed. It is further pointed out that due to the actuating force being sustained directly by the bolster at the opposite end of the car to which the buffing action is applied, the underframe construction and center sills between said bolster and the adjacent end of the car will not be affected, and that the underframe and center sill construction, between the bolster, will be subjected to tension only, thus preventing buckling of the underframe structure. When the actuating force has been reduced, the expansive action of the friction shock absorbing mechanisms C will restore the parts to their normal position.

Assuming a draft action as being applied to the drawbar 15 at the left-hand end of Figure 1, the initial action produced by the outward movement of the drawbar 15 will be a compression of the spring resistance G at that end of the car. The compression of the spring G will continue until the key F engages the front end walls of the openings 38 and 39 of the stop castings 37 and the channel members H. During the forward movement of the yoke D, the follower K will be held stationary with respect to the channel members H, thereby providing solid abutment means for the spring G. Upon the key F engaging the end walls of the slots in the stop castings and channel members, the channel members H will be forced to move outwardly in unison with the drawbar 15. During this action the stop castings 36 at the opposite end of the car will force the friction shock absorbing mechanism C at that end of the car forwardly, compressing the same and compressing the other friction shock absorbing mechanism C against the abutment 25 of the bolster 10. The pressure is transmitted from the wedge 44 of one friction shock absorbing mechanism to the wedge 44 of the other, by means of the column element B, as hereinbefore described. The compression of the friction shock absorbing mechanism C at the opposite ends of the car will continue either until the actuating force is reduced or further compression of the friction shock absorbing mechanism is prevented by the opposite ends of the column element B coming into engagement with the ends of the friction shells. All of the parts will be restored to the normal position upon the actuating force being reduced by the expansive action of the spring resistance elements in the friction shock absorbing mechanisms C and the expansive action of the springs G associated with the yokes D.

From the preceding description, taken in connection with the drawings, it will be clear that the springs G serve as yielding means

during the first part of the draft action, to permit starting of the train of cars and also absorb relatively light shocks, while the friction shock absorbing mechanisms C are available to absorb the heavier shocks to which the mechanism is subjected. 70

Referring next to the embodiment of the invention illustrated in Figure 6, the same includes movable members M which correspond to the movable members H of the embodiment of the invention hereinbefore described. The members M are arranged in the same manner as the members H and have stop castings thereon which co-operate with friction shock absorbing means disposed between the bolsters actuated through the medium of an interposed column member, all these parts being similar to those hereinbefore described in connection with the embodiment illustrated in Figures 1 to 5 inclusive. Side stop castings are secured to the inner faces of the members M in any well known manner, the same being preferably secured by rivets. The castings 60 are provided with front and rear outer stop shoulders 61-61 and front and rear inner stop shoulders 62-62. The drawbar is indicated by 63 and is connected to the yoke member 64 by means of a transverse key 65 working in slots 66 in the castings 60. The parts 63, 64 and 65 correspond to the drawbar 15, the yoke D and the key F hereinbefore described. Front and rear follower members 67 and 68 are disposed within the yoke and co-operate with the stop shoulders of the castings 60. A coiled spring 69 is interposed between the followers. The arrangement as shown, is such that the front follower 67 co-operates with the front outer stop shoulder 61 and the front inner stop shoulder 62, while the rear follower 68 co-operates with the rear outer stop shoulder 61, and the rear inner stop shoulder 62. The arrangement is such as to provide compression of the spring 69 in both buff and draft, so that the spring will be actuated before the members M are moved with respect to the car body. As will be evident, the spring shock absorbing mechanism just described serves as yielding means during the first part of both the draft and buffing action, to permit starting of the train of cars, and also absorb relatively light shocks. 110

While I have herein shown and described what I consider the preferred manner of carrying out the invention, the same is merely illustrative, and I contemplate all changes and modifications which come within the scope of the claims appended hereto. 115

I claim:

1. In a railway car underframe, the combination with front and rear body bolsters; of longitudinally disposed continuous pressure transmitting members movable lengthwise of the car, said pressure transmitting members extending from end to end of the 125

car underframe and receiving the buffing and draft forces; shock absorbing means at each end of the car, both of said shock absorbing means being interposed between said

bolsters; and means for transmitting the actuating force from said pressure transmitting members through said shock absorbing means at both ends of the car to the bolster at one end only of the car in draft, and through the shock absorbing means at both ends of the car to the bolster at the other end only of the car in buff.

2. In a railway car underframe, the combination with body bolsters at opposite ends of the car; of longitudinally disposed continuous pressure transmitting members movable lengthwise of the car with respect to the body bolsters, said pressure transmitting members extending from end to end of the car underframe and beyond the bolsters and receiving the buffing and draft forces; shock absorbing means interposed between said bolsters, said shock absorbing means being disposed at opposite ends of the car; abutment means on each of said bolsters opposing outward movement of the shock absorbing means at the same end of the car; a column element interposed between said shock absorbing means; and means on said pressure transmitting members for actuating the shock absorbing means in both buff and draft.

3. In a railway car, the combination with front and rear body bolsters; of longitudinally disposed continuous pressure transmitting members movable lengthwise of the car, said pressure transmitting members extending from end to end of the car underframe and receiving the buffing and draft forces; drawbar means anchored to the opposite ends of said pressure transmitting members and adapted to receive the buffing and draft forces; a shock absorbing element adjacent each bolster, said shock absorbing elements being interposed between said bolsters; and means for transmitting the actuating force from said pressure transmitting members through the shock absorbing elements to the bolster at one end of the car in draft and to the bolster at the other end of the car in buff.

4. In a railway car, the combination with front and rear body bolsters; of longitudinally disposed continuous pressure transmitting sills, movable lengthwise of the car with respect to the body bolsters; drawbar members at opposite ends of said sills and having lost motion connection therewith; spring shock absorbing means opposing relative movement of the drawbar and sills during draft; shock absorbing means interposed between said bolsters; and means for transmitting the actuating force from said sills to said shock absorbing means simultaneously, said means including a column element interposed between the shock absorbing means,

movement of said shock absorbing means being resisted by engagement with one of the bolsters in draft and by the other bolster in buff.

5. In a railway car, the combination with body bolsters disposed at opposite ends of the car; of longitudinally extending draft sills fixed to the body bolsters; longitudinally extending draft sills movable with respect to said fixed sills; drawbar members connected at opposite ends to said movable draft sills and adapted to receive buffing and draft shocks; friction shock absorbing mechanisms disposed adjacent each of said bolsters; a pressure transmitting column element interposed between said friction shock absorbing mechanisms; and means for transmitting the actuating force directly from said movable sills to one of said friction shock absorbing mechanisms in draft and to the other of said friction shock absorbing mechanisms in buff.

6. In a railway car, the combination with body bolsters at opposite ends of the car; of longitudinally disposed fixed center sills secured to the body bolsters; relatively movable, longitudinally disposed pressure transmitting sills disposed between said center sills, said pressure transmitting sills receiving the actuating force in buff and in draft; abutment means on each of said bolsters; a friction shock absorbing mechanism co-operating with the abutment means of each bolster; a pressure transmitting column interposed between said friction shock absorbing mechanisms; and abutment means on the pressure transmitting sills adjacent the opposite ends thereof and adapted to respectively co-operate with said friction shock absorbing mechanisms.

7. In a railway car, the combination with body bolsters at opposite ends thereof; of longitudinally disposed sills extending through said bolsters and movable longitudinally of the car, said sills being adapted to receive the draft and buffing shocks; stop means adjacent the opposite ends of said sills; abutment means on each of said bolsters; a friction shock absorbing mechanism co-operating with abutment means of each bolster and the stops at the corresponding end of the sills; and a pressure transmitting column interposed between said friction shock absorbing mechanisms.

8. In a railway car, the combination with body bolsters at opposite ends of the car; pressure transmitting members extending through said bolsters; drawbar means attached to the opposite ends of said members; stop means on each bolster; shock absorbing means interposed between said stop means on the bolsters, said shock absorbing means including separate shock absorbing elements cooperating with each bolster; means for transmitting the actuating force from said members to each of said shock absorbing ele-

ments; and means for transmitting the force from one shock absorbing element to the other, whereby the force is transmitted through said shock absorbing means to the

5 bolster at one end of car in draft and to the bolster at the other end of the car in buff.

9. In a railway car underframe, the combination with front and rear body bolsters; longitudinally disposed members movable 10 lengthwise of the car and adapted to receive the buffing forces directly from the coupler at one end of the car; a longitudinally disposed column member independent of the car body, shock absorbing means reacting between said member and column, said column being actuated by said first named members 15 through said shock absorbing means; and friction shock absorbing means interposed between said column member and the bolster at 20 the opposite end of the car.

10. In a railway car, the combination with body bolsters at opposite ends of the car; movable draft sills extending through said bolsters, said draft sills being adapted to receive the buffing and draft forces; shock absorbing means interposed between said bolsters including a shock absorbing mechanism adjacent each bolster and held against movement in one direction by said bolster; 25 means for transmitting the actuating force from said draft sills through said shock absorbing means to the bolster at one end of the car in draft, and to the bolster at the other end of the car in buff, said last named means including a column element interposed between said shock absorbing mechanisms; and supporting means for said column element, said supporting means being disposed at the opposite ends of said column element.

40 11. In a railway car underframe, the combination with sill members movable longitudinally with respect to the underframe structure; body bolsters, said body bolsters having openings therethrough adapted to receive the 45 sill members for sliding movement, said opening having removable bottom walls to permit withdrawal of the sills; shock absorbing means disposed between said sills and co-operating with the body bolsters at the opposite 50 ends of the car; a pressure transmitting column element interposed between said shock absorbing mechanisms; tie plates connecting the bottom portions of the sills and supporting the shock absorbing mechanisms and pressure transmitting column, said tie plates being detachable to permit removal of the shock absorbing mechanisms and column member; yoke means at the opposite ends of said sills and having limited movement with 55 respect thereto; yielding means for opposing relative movement of said yoke means and sills; a drawbar connected to each of said yoke means; and tie plates at the opposite ends of said sills secured to the bottom thereof, and 60 serving as supporting means for the yoke 65

means, said last named tie plates being detachable to permit removal of the yoke means, drawbar and yielding means, and parts co-operating therewith.

12. In car construction, the combination with a car underframe including bolsters; of a pair of longitudinally separated shock absorbing devices located intermediate the bolsters; a pressure-transmitting column interposed between said shock absorbing devices; 70 couplers at each end of the car; and pressure-transmitting means operatively connected to each coupler, each pressure transmitting means being movable with respect to the column and extending from the coupler inwardly of the adjacent bolster and adapted to apply pressure in buff to the corresponding adjacent shock absorbing device to actuate the same, the pressure being transmitted through the latter to said column and through the column to the other shock absorbing device. 75

13. In a draft rigging for railway cars, the combination with a car underframe structure including bolsters at opposite ends of the car and center sills fixed to said bolsters; of coupler means at opposite ends of the car; shock absorbing means actuated through said couplers in buff; and floating means for transmitting the actuating force in buff from the coupler at one end of the car through said shock absorbing means to the bolster at the other end only of the car. 80

14. In a railway draft rigging for railway cars, the combination with a car underframe structure including stop members at opposite ends of the car and center sills fixed to said stop members; of coupler means at opposite ends of the car; shock absorbing means actuated through said couplers; and floating means for transmitting the buffing shocks from the coupler at either end of the car through said shock absorbing means to the stop means at the opposite end only of the car. 100

15. In a draft rigging for railway cars, the combination with fixed bolsters at opposite ends of the car and center sills fixed thereto; of a coupler at one end of the car; shock absorbing means actuated by said coupler in buff; and means for transmitting the actuating force in buff from said coupler through the shock absorbing means to the bolster at the opposite end only of the car, said means including a longitudinally disposed floating column element interposed between said bolsters. 110

16. In car construction, the combination with body bolsters at opposite ends of the car; of a coupler at each end of the car; and means for transmitting buffing shocks received by the coupler at each end of the car to the bolster at the opposite end of the car, said means including cushioning means and a cooperating floating column element disposed between said bolsters. 125

17. In car construction, the combination 130

with body bolsters at opposite ends of the car; of a coupler at each end of the car; and means for transmitting buffing shocks from each coupler to the bolster at the other end of the car, said means including a cushioning member inwardly of each bolster and a floating column interposed between said cushioning members.

18. In car construction, the combination with body bolsters at opposite ends of the car; of a coupler at each end of the car; means for transmitting buffing shocks from the coupler at each end of the car to the bolster at the opposite end of the car, including a floating column member and cushioning means, said column member being located and terminating between said bolsters.

19. In a railway draft rigging, the combination with an underframe structure including bolsters at opposite ends of the car; of coupler means at opposite ends of the car; and means actuated through inward movement of either coupler for transmitting the actuating force in buff from the coupler at one end of the car to the bolster at the opposite end of the car, said means including pressure-transmitting means and cooperating shock absorbing means, said pressure-transmitting means including a floating column element disposed between said bolsters.

20. In car construction, the combination with the underframe structure of the car including body bolsters at opposite ends of the same; of a coupler at each end of the car; a floating cushioning means between said bolsters, including a shock absorbing device on the inner side of each bolster and a floating column interposed between said devices, each shock absorbing device being held against outward movement by the corresponding bolster; and pressure transmitting means movable with respect to said bolsters for transmitting buffing forces from each coupler to said floating cushioning means.

21. In a railway draft rigging, the combination with center sills and bolsters at opposite ends of the car rigid with said sills; of a cushioning device adjacent the inner side of the bolster at one end of the car; a floating column load-transmitting element between said cushioning device and the bolster at the other end of the car; a coupler at each end of the car; and means for transmitting buffing shocks from the coupler at said last named end of the car to the corresponding end of the floating column element to force the latter toward the bolster at the other end of the car and compress the shock absorbing device at that end of the car against said bolster.

22. In a railway draft rigging, the combination with center sills and bolsters at opposite ends of the car rigid with said sills; of a cushioning device adjacent the inner side of one of said bolsters; a floating column load-transmitting element between said cushioning device and the other bolster; a coupler at each end of the car; and means operatively connected to the coupler at the end of the car at which the last named bolster is located for transmitting buffing shocks to the corresponding end of said floating column element.

23. In a railway draft rigging, the combination with center sills and bolsters at opposite ends of the car rigid with said sills; of a cushioning device adjacent the inner side of the bolster at one end of the car; a floating column load-transmitting element between said cushioning device and the bolster at the other end of the car; a coupler at each end of the car; and means operatively connected to said coupler at said last named end of the car for transmitting buffing shocks to the corresponding end of said column element and draft shocks to the cushioning device at the other end of said column element.

24. In a railway draft rigging, the combination with center sills and bolsters at opposite ends of the car rigid with said sills; of means for resisting shocks, including a cushioning device adjacent the inner side of each bolster, and a floating column load-transmitting element between said cushioning devices; a coupler at each end of the car; and means for transmitting buffing shocks from each coupler to the corresponding end of said means for resisting shocks, said means including a shock absorbing device cooperating with the coupler.

25. In a railway draft rigging, the combination with center sills and bolsters at opposite ends of the car rigid with said sills; of means for opposing shocks including a cushioning device adjacent the inner side of each bolster, and a floating column load-transmitting element between said cushioning devices; a coupler at each end of the car; and means for transmitting buffing and draft shocks from each coupler to said means for opposing shocks including a shock absorbing device cooperating with said coupler, said shock absorbing device being operated in both buff and draft.

26. In car construction, the combination with an underframe including spaced bolsters and center sills extending therebetween and rigidly connected thereto; of a cushioning system interposed between the bolsters and located between the center sills, said system including a shock absorbing device adjacent each bolster and a floating column element longitudinally interposed between said shock absorbing devices; a coupler at each end of the car; and means operatively associated with each coupler for actuating said cushioning system.

In witness that I claim the foregoing I have hereunto subscribed my name this 23rd day of December, 1927.

STACY B. HASELTINE.
